US00D786862S

(12) **United States Design Patent** (10) **Patent No.:** **US D786,862 S**
(45) **Date of Patent:** **** May 16, 2017**

(54) **WEARABLE ELECTRONIC DEVICE**

(71) Applicant: **LG ELECTRONICS INC.**, Seoul
(KR)

(72) Inventors: **Seala Park**, Seoul (KR); **Dongsoon Kim**, Seoul (KR); **Chanwoo Park**, Seoul (KR)

(73) Assignee: **LG ELECTRONICS INC.**, Seoul
(KR)

(**) Term: **15 Years**

(21) Appl. No.: **29/534,899**

(22) Filed: **Jul. 31, 2015**

(30) **Foreign Application Priority Data**

Feb. 3, 2015 (KR) 30-2015-0005935

(51) **LOC (10) Cl.** **14-02**

CLAIM

The ornamental design for a wearable electronic device, as shown and described.

DESCRIPTION

FIG. 1 is a perspective view of a wearable electronic device showing our new design;

FIG. 2 is a front view thereof;

FIG. 3 is a rear view thereof;

FIG. 4 is a left side view thereof where the right side view is a mirror image;

FIG. 5 is a top plan view thereof; and,

(Continued)

FIG. 6 is a bottom plan view thereof.
The broken lines depict portions of the wearable electronic device that form no part of the claimed design.

1 Claim, 6 Drawing Sheets
